UNITED STATES PATENT OFFICE

2,684,605

COOLING BED

Edward T. Peterson, Reading, Pa., assignor to
 Birdsboro Steel Foundry and Machine Company, Birdsboro, Pa., a corporation of Pennsylvania

Continuation of abandoned application Serial No. 173,657, July 13, 1950. This application December 14, 1951, Serial No. 261,833

10 Claims. (Cl. 80—42)

1

The present invention relates to cooling beds or hot beds of the type which support, manipulate and permissibly control the cooling of metallic products from a hot working rolling mill, such as bars, strip, shapes and other stock.

The present application is a continuation of U. S. application Serial No. 173,657, filed July 13, 1950, for cooling bed, and now abandoned.

A purpose of the invention is to cheapen the construction of cooling beds by eliminating the necessity of long linkages for operating the beds, while retaining the advantage of balance of the parts to minimize the amount of work which must be done by the drive.

A further purpose is to reduce the cost of installation of beds by eliminating the necessity for a deep pit foundation, and permit the bed mechanism to be located very close to the shuffle bars.

A further purpose is to reduce the number of bearings and other machined surfaces required in the construction of a cooling bed.

A further purpose is to accomplish the entire drive of the cooling bed from a single eccentric shaft which manipulates both sets of cooling bed bars.

Further purposes appear in the specification and in the claims.

In the drawings I have chosen to illustrate a few only of the numerous embodiments in which my invention may appear, selecting the forms shown from the standpoints of convenience in illustration, satisfactory operation and clear demonstration of the principles involved.

Figure 1 is a fragmentary partially diagrammatic vertical section of a cooling bed embodying the principles of the invention, the section being taken longitudinally of the carry over bars at a position corresponding with the line 1—1 of Figure 5.

Figure 2 is a view corresponding to Figure 1 illustrating a bed similar to Figure 1, without the run-out mechanism and with a somewhat different approach table.

Figure 3 is a view corresponding to Figure 1 showing a bed arranged for pack annealing on the flat sides of the carry over bars.

Figure 4 is an enlarged section of Figures 1, 2 or 3 on the line 4—4.

Figure 5 is an enlarged section of Figures 1, 2 or 3 on the line 5—5.

Figure 6 is an enlarged section of Figures 1, 2 or 3 on the line 6—6.

Figure 7 is an enlarged section of Figures 1, 2 or 3 on the line 7—7.

Describing in illustration but not in limitation and referring to the drawings:

2

In the prior art, cooling beds of the character employed in connection with rolling mills especially for manufacture of steel bars, strip and shapes have commonly included two sets of coolings bed bars or carry over bars extending transversely to the direction of progression of the stock, and suitably notched or plain as desired, the sets of carry over bars being supported on very long linkages from rocker shafts which raise one set of carry over bars and lower another set of carry over bars. This prior art construction has the advantage of minimizing the amount of power required to operate the cooling bed, since one set of carry over bars and its supporting beams and driving mechanism balances the other set, and the main drive must merely move the weight of the stock on the bed and overcome the operating friction. Beds of this character have, however, been very expensive to build and install. A comparatively large number of shafts and bearings are needed, and the very long linkages which operate the sets of carry over bars are expensive to manufacture and costly to install. The installation is costly particularly because a very deep pit is required to allow for the necessary height of the drive.

By the present invention, the advantages of a balanced construction are obtained, so that the weight of one set of bars can compensate for the weight of the other set of bars, as far as the drive is concerned, but the long and costly linkages and the elaborate and expensive drive of the prior art bed are eliminated. The entire structure including the drive can be placed immediately beneath the carry over bars, thus economizing on material and workmanship and the depth of the pit and foundation are greatly reduced. The number of bearings and other machined surfaces is also reduced, thus further decreasing the cost.

The cooling bed of the invention comprises a first set of carry over bars 20 which extend lengthwise of the direction of motion of the stock or transversely to the length of the stock in side by side parallel relationship, and a second set of carry over bars 21 similar to the first, interspersed among the first in alternate relationship and adapted to move with respect to the first so that one set of carry over bars moves vertically and longitudinally with respect to the other set.

As well known in the art, the top surface of the carry over bars may be of any desired character depending on the ideas of the designer, some preferring smooth surfaces and some preferring notches of various characters, but for convenience in illustration the surface has been shown notched at 22 on all bars.

3

The first set of carry over bars 20 is supported, secured to and mounted at one end on beams 23 and at the other end on beams 24, while the second set of carry over bars 21 is supported at one end by a beam 25 and at the other end by a beam 26. The beams run transversely to the carry over bars. The beams 23, 24, 25 and 26 are all substantially of the same length and end at the same position and, depending upon the desired width of the bed, any number of combinations of first and second carry over bar sets with their supporting beams 23, 24, 25 and 26 can be arranged side by side as shown in the drawings, particularly Figures 4 to 7.

The carry over bars of each set and the beams of each set make a rigid frame structure which is suitably connected together as by bolting, riveting or welding.

The first set of carry over bars 20 are manipulated by motion of the supporting beams 23 and 24. Beam 23 is mounted on fixed pivots 27 supported in bearings 28 from bearing mounting 30 on foundation 31. As best seen in Figure 4, the fixed pivots 27 are connected to opposite ends of each beam 23 so that several sets of first carry over bars are pivotally mounted on the same axis, one beside another.

As best seen in Figures 1, 2, 3 and 5, an eccentric shaft 32 built up of several elements desirably extends laterally of the entire cooling bed and is driven suitably by an electric motor (not shown). The shaft 32 is supported in bearings 33 mounted on the foundation 31.

The shaft 32 is conveniently made up in sections, consisting of an eccentric or crank portion 34 adjacent the ends of the beams, carrying suitable integral bearing portions 35 journaling in the bearings 33 and interconnected by desirably tubular shaft connections 36. The shaft connections 36 allow for the expansions of the long eccentric shaft, by providing for relative longitudinal adjustment of position between externally splined collars 37 secured on the ends of the eccentric portions 34 beyond the bearing portions 35 by keys 38, and having longitudinal splined grooves 40 which are engaged by suitable splines 40' on the inside of heads 41 secured on the ends of the tubular shaft portions 36 by bolts 42. The heads have freedom for longitudinal motion at the ends 43 and 44 with respect to the splined collars to permit adjustment for expansion and contraction.

The various eccentric portions 34 are provided with anti-friction bearing material 45 and are surrounded by eccentric straps 46 which are separated at 47 into two strap portions. Eccentric rollers 48 also surround the eccentrics and are freely movable around the eccentric axis independently of the motion of the straps.

At the positions corresponding to the ends of the beams, rockers 50 best seen in Figures 1, 2, 3, 5 and 6 extend generally horizontally beneath the carry over bars. The rockers are pivoted intermediate their ends and preferably near the middle on pivots 51 supported on bearings 52 from foundations 53. One end 54 of each rocker 50 extends beneath the corresponding eccentric and engages the bottom of eccentric roller 48 so that the motion of the rocker follows the motion of the eccentric. Since the weight of one end of one set of carry over bars is bearing down on the other ends of the rockers, the end 54 of the rockers always maintains contact with the eccentric rollers.

The opposite end of each rocker 50 makes piv-

5 otal connection at 55 with an upwardly extending link 56. The upper end of each link 56 makes pivotal connection at 57 with one end of each beam 24 (Figure 6). The links 56 are adjustable in length for the purpose of aligning the top of the carry over bars by a nut 58 surrounding oppositely threaded bolt portions 60 (Figure 6) from the respective ends of each link 56.

10 The set of carry over bars 21 is manipulated by the eccentric straps 46. The opposite ends of beams 25 rest on and are secured to the tops of the eccentric straps by bolts 61 at one end of each beam (Figure 5) and by bolts 62 at the other end of each beam. The bolts 62 are provided with springs under the nuts and adequate clearance for resilient adjustment as the beams expand and contract.

15 The beams 26 at the opposite end of the set of carry over bars 21 carry at one end rotatable rollers 63 resting on track 64 on foundation 65 and at the other end carry rollers 63' which engage similar tracks 64. Rollers 63 are flanged at 66 (Figure 7) so as to engage on both sides of the track and thus maintain their lateral position, whereas the roller 63' at the opposite ends of beams 26 are without flanges so that they can move laterally of the tracks as well as longitudinally of the tracks to allow for expansion and contraction.

20 It has been found desirable to employ a new set of carry over bars every 15 feet laterally of the bed. It will be seen from Figures 4 to 7 that the beams do not run continuously beyond a single set, but at the ends of each set have provision for expansion and contraction either by movements axially of the pivots in Figure 4 or movements along the straps in Figure 5, movements axially of the pivots in Figure 6 or movements axially of the rollers in Figure 7.

25 The novel cooling bed of the invention may be used with any desired combination of run-in table, pack annealing bed, and run-out table, and different forms are shown in Figures 1, 2 and 3, the differences forming no part of the present invention, but serving merely to illustrate that the cooling bed of the invention can be employed in these various combinations. In Figure 1 a run-in table 67 of any well known character has individual driving motors 68, a lifting apron 70 and kick-off mechanism 71. The stock from the run-in table is dropped into a straightening notch 72, from which it is removed by the notch bars.

30 In Figure 2 the approach table rolls 67 are driven in any suitable manner by line shaft 68' and the apron 70' may conveniently be stationary, the other features being the same as in Figure 1.

35 In Figure 3 a hand pack annealing bed 72' has been substituted for the non-packing bed and a walkway 72" is provided for personnel. The plunger lift shown at 72' permits discharging bars on to the cooling bed to form and maintain a pack.

40 The run-out table shown in Figures 1 and 3 and omitted in Figure 2 may be of any suitable form, here comprising shuffle bars 73 operated by an eccentric 74 of well known character and raised or depressed as desired by lifting levers 75. Run-out rolls are provided at 76.

45 In operation, the carry over bar set 20 has fixed pivotal mounting at one end at the beam 23 and moves up and down at the opposite end at the beam 24 under the action of the eccentric, the eccentric roller and the remote end of the rocker acting through the link. The carry over bar set 21 moves up and down and back and forth at the

end supported on the beam 25 under the action of the eccentric strap. At the end supported on the track rollers, adjoining the beam 26, the shuffle bars 21 pivot about the track rollers and also move back and forth as the rollers travel along the track to provide the horizontal motion required by the eccentric.

Thus one set of carry over bars 20 are on a fixed pivot at one end and the other set of carry over bars 21 move back and forth and up and down at that end. At the opposite end, the set of carry over bars 21 pivot and move back and forth, while the other set of carry over bars 20 move up and down.

It will be evident that either set of carry over bars may be in advance of the others at a given eccentric position, and the following description is merely an example of one of the possible operative relationships.

The relative motion of the bars is always opposite. Thus in this example when the eccentric, moving clockwise in Figures 1 to 3, begins to move beam 25 toward the right and down, the eccentric roller pushes down on end 54 of rocker 50 and moves the opposite end of the rocker and beam 24 up, so that while one end of carry over bar set 21 is moving down the opposite end of carry over bar set 20 is moving up. When the eccentric continues its clockwise motion in Figures 1 to 3 and begins to move to the left and up, beam 25 moves up and carry over bar set 21 moves to the left, while the eccentric roller moves up and allows end 54 of rocker 50 to move up carrying the opposite end, link 56 and beam 24 down.

Thus in effect the vertical motion at either end of the bed is largely confined to one set of carry over bars, the set of carry over bars 21 providing the vertical motion at the left end and the set of carry over bars 20 providing the vertical motion at the right end. The horizontal motion is provided entirely by the set of carry over bars 21.

It will be evident that by the invention the construction of cooling beds has been rendered simple, inexpensive and easy to install, while at the same time maintaining the balanced action, since when one end of one set of carry over bars is moving up the other end of the other set of carry over bars is moving down. The load on the eccentric is also balanced, since while one end of one set of carry over bars always presses down on the eccentric the load from the other end of the other set of carry over bars is always up.

The invention also results in simplifying the construction and reducing the mass to be moved because one end of each set of carry over bars pivots and is not required to move vertically in this mechanism, while in the prior art it has been customary to move both ends of both sets vertically.

In view of my invention and disclosure variations and modifications to meet individual whim or particular need will doubtless become evident to others skilled in the art to obtain all or part of the benefits of my invention without copying the structure shown, and I, therefore, claim all such insofar as they fall within the reasonable spirit and scope of my claims.

Having thus described my invention what I claim as new and desire to secure by Letters Patent is:

1. In a cooling bed, a plurality of sets of carry over bars extending generally horizontally in the same general direction, intermingled with one another and adapted to move relatively up and

down and forward and backward, a pivotal mounting for one end of the first set of bars, a pivotal mounting for the opposite end of the second set of bars, an eccentric, an eccentric strap on the eccentric connected to the one end of the second set of bars, a rocker having pivotal mounting intermediate its ends operatively connected at one end to the eccentric and a link pivotally connecting the opposite end of the rocker with the opposite end of the first set of bars.

2. In a cooling bed, a plurality of sets of carry over bars extending generally horizontally in the same general direction, intermingled with one another and adapted to move relatively up and down and forward and backward, a fixed pivotal mounting for one end of the first set of bars, a roller secured to the opposite end of the second set of bars, a track for the roller located beneath the roller, an eccentric, a strap on the eccentric connected to the one end of the second set of bars, a rocker having pivotal mounting intermediate its ends operatively connected at one end with the eccentric and a link pivotally connecting the opposite end of the rocker with the opposite end of the first set of bars.

3. In a cooling bed, a plurality of sets of carry over bars extending generally horizontally in the same general direction, intermingled with one another and adapted to move relatively up and down and forward and backward, a beam extending transversely under each set of bars near each end thereof and supporting the bars of each set, a pivotal mounting for the beam under one end of the first set of bars on a generally horizontal axis, a pivotal mounting for the beam under the opposite end of the second set of bars on a generally horizontal axis, an eccentric on a generally horizontal axis beneath the bars adjoining the end at which the first set of bars has pivotal mounting, a strap on the eccentric connected to the beam under the second set of bars at the end opposite from the pivotal mounting of the second set, a rocker extending longitudinally beneath the bars having pivotal mounting intermediate its ends on a generally horizontal axis, operatively connected at one end with the eccentric and a link pivotally connecting the opposite end of the rocker with the beam under the end of the first set of bars opposite to the end at which the first set of bars is pivotally mounted.

4. In a cooling bed, a plurality of sets of carry over bars extending generally horizontally in the same general direction, intermingled with one another and adapted to move relatively up and down and forward and backward, a beam extending transversely under each set of bars near each end thereof and supporting the bars of each set, a fixed pivotal mounting for the beam under one end of the first set of bars on a generally horizontal axis, a roller mounted on the beam under the end of the second set of bars opposite to the end at which the first set of bars is pivotally mounted, a track under and supporting the roller, an eccentric beneath the bars extending generally horizontally and located adjacent the end at which the first set of bars is pivotally mounted, an eccentric strap on the eccentric connected to the beam under the end of the second set of bars opposite to the end at which the roller is mounted, a rocker extending generally horizontally beneath the bars and longitudinally thereof, having generally horizontal pivotal mounting intermediate its ends and operatively connected at one end of the rocker with the eccentric, and a link pivotally connected to the end of the rocker op-

posite to that operatively connected with the eccentric, upwardly extending from the rocker and pivotally connected with the beam under the first set of bars at the end opposite to the end at which the first set of bars is pivotally mounted.

5. In a cooling bed, a plurality of sets of carry over bars extending generally horizontally in the same general direction, intermingled with one another and adapted to move relatively up and down and forward and backward, beams extending transversely under each end of each set of bars and mounting the bars on the beams, pivots at the opposite ends of the beam under one end of the first set of bars, pivots at the opposite ends of the beam under the end of the second set of bars remote from the end at which the pivots are provided for the first set of bars, eccentrics extending generally transversely beneath the sets of bars adjacent the end at which the pivots are provided for the first set of bars, the eccentrics being located at positions adjoining the ends of the beams, eccentric straps on the eccentrics connected to the ends of the beam which is under the second set of bars at the end of the bars adjoining that at which the first set is pivotally mounted, rockers extending longitudinally beneath the bars at positions adjoining the ends of the beams, each rocker having generally horizontal pivotal mounting intermediate its ends, each rocker being operatively connected at one end with one of the eccentrics, and links pivotally connected with the opposite ends of the respective rockers and pivotally connected with the ends of the beam under the end of the first set of bars remote from the end at which the first set of bars is provided with pivotal mounting.

6. In a cooling bed, a plurality of sets of carry over bars extending generally horizontally in the same general direction, intermingled with one another and adapted to move relatively up and down and forward and backward, beams extending transversely under each end of each set of bars and mounting the bars on the beams, fixed pivots for the opposite ends of the beam under one end of the first set of bars, rollers secured to the opposite ends of the beam under the end of the second set of bars remote from the end at which the fixed pivots are located, tracks beneath the rollers, an eccentric shaft having eccentrics located at positions corresponding to the ends of the beams, the shaft extending horizontally beneath the bars and adjoining the end of the bars at which the fixed pivots are located, rockers extending longitudinally of the bars at positions corresponding to the ends of the beams having horizontal pivotal mounting intermediate their ends, operatively connected at one end of each rocker with one of the eccentrics and a link pivotally connecting the opposite end of each rocker with one end of the beam under the first set of bars adjoining the end at which the rollers are located.

7. In a cooling bed, a plurality of sets of carry over bars extending generally horizontally in the same general direction, intermingled with one another and adapted to move relatively up and down and forward and backward, beams extending transversely under each end of each set of bars and mounting the bars on the beams, a pivotal mounting for the ends of the beam under one end of the first set of bars, a pivotal mounting for the ends of the beam under the end of the second set of bars remote from the pivotal mounting of the first set of bars, an eccentric shaft extending horizontally beneath the bars

adjoining the end of the pivotal mounting for the first set of bars and having at positions corresponding to the ends of the beams an eccentric, an eccentric strap on each eccentric connected to the ends of the beam under the second set of bars at the end adjoining the pivotal mounting of the first set of bars, a roller on each eccentric, rockers extending longitudinally beneath the bars at positions corresponding to the ends of the beams, having pivotal mounting intermediate their ends and each rocker at one end extending beneath and engaging one of the rollers and a link pivotally connecting the opposite end of each rocker with the end of the beam beneath the first set of bars at the end of the first set of bars remote from the pivotal mounting of the first set.

8. In a cooling bed, a plurality of sets of carry over bars extending generally horizontally in the same general direction, intermingled with one another and adapted to move relatively up and down and forward and backward, beams extending transversely under each end of each set of bars and mounting the bars on the beams, horizontal fixed pivotal mounting for the opposite ends of the beam under one end of the first set of bars, track rollers mounted on opposite ends of the beam under the end of the second set of bars remote from the pivotal mounting of the first set of bars, rails under and supporting the track rollers, an eccentric shaft extending horizontally under the bars at a position adjoining the pivotal mounting of the first set of bars and having eccentrics at positions corresponding with the ends of the beams, an eccentric strap on each eccentric and connected to one of the opposite ends of the beam under the end of the second set of bars adjoining the pivotal mounting of the first set of bars, an eccentric roller on each eccentric, rockers extending longitudinally beneath the bars at positions corresponding with the ends of the beams, having generally horizontal pivotal mounting intermediate their ends and one end of each rocker extending below and engaging each eccentric roller on each eccentric, and links pivotally connecting the opposite ends of the rockers respectively with the ends of the beam under the first set of bars adjoining the first rollers.

9. In a cooling bed, a plurality of sets of carry over bars extending generally horizontally in the same general direction, intermingled with one another and adapted to move relatively up and down and forward and backward, beams extending transversely under each end of each set of bars and mounting the bars on the beams, horizontal fixed pivotal mounting for the opposite ends of the beam under one end of the first set of bars, track rollers mounted on opposite ends of the beam under the end of the second set of bars remote from the pivotal mounting of the first set of bars, rails under and supporting the track rollers, one track roller and its track having flange engagement which guides the track roller laterally and the other track roller and its track being free from flange engagement and laterally movable, an eccentric shaft extending horizontally under the bars at a position adjoining the pivotal mounting of the first set of bars and having eccentrics at positions corresponding with the ends of the beams, an eccentric strap on each eccentric and connected to one of the opposite ends of the beam under the end of the second set of bars adjoining the pivotal mounting of the first set of bars, an eccentric roller on each ec-

centric, rockers extending longitudinally beneath the bars at positions corresponding with the ends of the beams, having generally horizontal pivotal mounting intermediate their ends and one end of each rocker extending below and engaging each eccentric roller on each eccentric, and links pivotally connecting the opposite ends of the rockers respectively with the ends of the beam under the first set of bars adjoining the track rollers.

10. In a cooling bed, a plurality of sets of carry over bars extending generally horizontally in the same general direction, intermingled with one another and adapted to move relatively up and down and forward and backward, a fixed pivotal mounting for one end of the first set of bars, a sliding pivotal mounting for the opposite end of the second set of bars, a common eccentric, a

5 rocker fixedly pivoted intermediate its ends and operatively connected at one end to the eccentric, means operatively connecting the eccentric with the end of the second set of bars remote from the pivotal mounting of the second set of bars and means operatively connecting the rocker at the end remote from the eccentric with the opposite end of the first set of bars.
